CLAIM

The ornamental design for a therapeutic applicator, as shown and described.

DESCRIPTION

FIG. 1 is a perspective view of a therapeutic applicator; FIG. 2 is a top plan view thereof; FIG. 3 is a front view thereof; FIG. 4 is a rear view thereof; FIG. 5 is a side view thereof; and, FIG. 6 is a bottom plan view thereof. The broken lines illustrate portions of the therapeutic applicator that form no part of the claimed design.
